UNITED STATES PATENT OFFICE.

EMIL P. VALLEY, OF CHICAGO, ILLINOIS.

ROLLER-TRUCK FOR PRINTING-PRESSES.

1,277,790.

Specification of Letters Patent. Patented Sept. 3, 1918.

Application filed August 8, 1917. Serial No. 185,096.

To all whom it may concern:

Be it known that I, EMIL P. VALLEY, a citizen of the United States, and a resident of the city of Chicago, county of Cook, and State of Illinois, have invented certain new and useful Improvements in Roller-Trucks for Printing-Presses, of which the following is a specification.

My invention relates to improvements in roller trucks for printing presses, and has for its object the provision of an improved construction of this character by means of which the form rollers of an ordinary printing press may be nicely and permanently adjusted to the type.

The invention consists in the combinations and arrangements of parts hereinafter described and claimed.

The invention will be best understood by reference to the accompanying drawings forming a part of this specification, and in which,

Figure 1 is a view of one end of a form roller equipped with a truck embodying my invention, and

Fig. 2 is a sectional view of the same.

The preferred form of construction as illustrated in the drawings comprises a sleeve 3 secured over each end of the ordinary shaft 4 of the ordinary form roller 5 of the press, said sleeve being secured in place by means of a set screw 6. A bearing member 7 is adjustably secured to each of the sleeves 3 by means of a set screw 8 as shown. The bearing member 7 is stepped, being provided with a central bearing surface 9 of largest diameter and bearing surfaces 10, 11, 12 and 13 arranged alternately on opposite sides thereof and of successively decreasing diameters.

By this arrangement it will be observed that by longitudinally adjusting the bearing member 7 on the corresponding sleeve 3 the different bearing surfaces 9, 10, 11, 12 and 13 may be brought into position to run upon the corresponding way 14 of the printing press 15 to nicely contact with the type 16, and that when such adjustment is once made it becomes practically permanent.

Also if desired, the bearing member 7 may be reversed on its sleeve to facilitate such adjustment. Owing to the stepped arrangement of the bearing surfaces with a central bearing surface of largest diameter and bearing surfaces on opposite sides thereof

and arranged alternately of successively decreasing diameters, comparatively deep shoulders are provided between adjacent bearing surfaces on the same side and at the same time comparatively delicate adjustments permitted.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A roller truck for printing presses comprising a bearing member adjustable longitudinally on the roller axis and provided with a stepped bearing face affording bearing surfaces of different diameters, the central of said bearing faces having the greatest diameter and those on each side successively alternately decreasing in diameter, substantially as described.

2. A roller truck for printing presses comprising a sleeve secured about the roller shaft; a bearing member adjustable longitudinally on said sleeve and provided with a stepped bearing face affording bearing surfaces of different diameters, the central of said bearing faces having the greatest diameter and those on each side successively alternately decreasing in diameter, substantially as described.

3. A roller truck for printing presses comprising a sleeve secured to the roller axis; and a bearing member reversible and adjustable longitudinally on said sleeve and provided with a stepped bearing face affording bearing surfaces of different diameters, the central of said bearing faces having the greatest diameter and those on each side successively alternately decreasing in diameter, substantially as described.

In testimony whereof I have signed my name to this specification in the presence of two subscribing witnesses.

EMIL P. VALLEY.
